CONTAINER ASSEMBLING DEVICE

James E. Annen, Kalamazoo, Mich., assignor to
Sutherland Paper Company, Kalamazoo, Mich.

Original application March 2, 1936, Serial No.
66,692. Divided and this application September
18, 1936, Serial No. 101,409

3 Claims. (Cl. 93—36)

This invention relates to improvements in container assembling devices.

This is a division of my application Serial No. 66,692, filed March 2, 1936, for containers and 5 assembling devices therefor.

The main object of this invention is to provide an apparatus or device for use in the setting up of cylindrical containers of box or container board or similar stock.

10 Other objects relating to details and economies of my invention will definitely appear from the description to follow. The invention is defined in the claims.

A preferred embodiment of my invention is 15 illustrated in the accompanying drawings, wherein:

Fig. 1 is a plan view of the side wall member blank forming a carton adapted to be assembled by my device.

20 Fig. 2 is a perspective view of the container in collapsed or knockdown form, illustrating the top and bottom members cooperative therewith to form the completely assembled container.

Fig. 3 is a view partially in side elevation and 25 partially in vertical section of the device or apparatus for use in assembling the parts of the container, the parts of which are shown in section.

Fig. 4 is a perspective view of the container 30 after the bottom portion has been assembled therewith on the device of the invention.

Fig. 5 is an enlarged detail sectional view on line 5—5 of Fig. 6, illustrating the relation of the container part as assembled on my device.

35 Fig. 6 is a fragmentary view partially in vertical section of my improved container in completely assembled condition.

Fig. 7 is a perspective view of the parts of my container in disassembled relation.

40 The improved container of my invention, as described in the above identified copending application, comprises a tubular side wall member 1, end walls 2 and 3, the end wall 3 being the top wall or cover, and the wall reinforcing or supporting and retaining bands or hoops 4 and 5, the hoops being duplicates but designated by separate numerals to facilitate description.

The side wall member is formed of a blank 6 of fibrous material such as box or container board 50 of suitable quality and thickness having a sealing flap 7 at one end which is lapped upon and glued to the other end of the wall member preferably further secured by means of the metal stitches or staples 8. The container is designed for the packaging of heavy materials and therefore the fas-

tening means 8 is very desirable in addition to the adhesive sealing means.

At each end thereof, the wall member is provided with outwardly disposed reversely folded segmental flaps 9. By reversely folded, I mean 5 that they are folded into approximately parallel relation with the sides of the container as clearly shown in the drawings.

The wall member is preferably longitudinally scored at 10 to permit collapsing, as shown in 10 Fig. 2, when the hoops or annular retaining members 4 and 5 are removed or before they are applied to assemble the parts. These hoops or annular retaining members have inwardly turned or beaded edges 11. The disk-like end members 2 15 and 3 are of such diameter as to fit within the hoop members and rest upon the outer beads or inturned edges thereof in overlapping relation to the ends of the container when the hoop members are in telescoping engagement with the ends 20 of the container. When the hoop members are pushed upon or telescoped upon the wall members, the flaps 9 are held under the compressive stress of the bead portion of the hoops, but as soon as the beads have passed beyond the edges 25 of the flaps, the flaps spring outwardly of their own resilience and engage behind the inner beads, thus securing the end members in position on the body.

To add to the holding capacity of the side 30 walls and flaps, they are preferably fluted at 12; that is, they have projecting lugs which very securely engage behind the inner beads of the hoops so that the bottoms or tops are capable of 35 withstanding a load imposed thereon when the container is filled without likelihood of the device accidentally opening.

When used as an ice cream container or as a dispensing container for other material which may be dipped from the container, I preferably 40 provide the top member with perforations 13 arranged in inwardly extending converging relation from one edge of the end member 3 and terminating in the U-shaped slit 14. Slits 15 are provided opposite the end of the U-shaped slit to facilitate 45 the engagement of a tool beneath the tongue portion 16 of the tearout 17. The tearout 17 enables the ready opening of the containers for dipping out the contents.

The containers as shown and described in my 50 copending application are well adapted for embodiment in containers of considerable length, such as may be used for the packaging or wrapping of linoleum, shade cloth, and rolled up fabrics or cloth and the like.

To facilitate the ready setting up of the container, I provide the packer with a device such as is illustrated in Fig. 3, consisting of an upright 18 mounted on a suitable base 19, the upright being preferably in the form of a rod or tube. On the top of this upright, I mount a disk 20 having a diameter corresponding to the internal diameter of the container, so that the wall member may be telescoped over the same as shown in Fig. 3. A base plate 21 is mounted for vertical adjustment on the upright and is secured in its adjusted position by means of set screw 22. The base plate carries a cone 23 having a diameter at its base or bottom 24 corresponding to the internal diameter of the cone.

In use, the base plate is adjusted to correspond to the length of the container to be set up and a container wall member 1 is telescoped over the top disk 20 and pushed down upon the base plate, the center cone 23 expanding the container to its circular form. The bottom hoop 4 with the bottom end disk assembled therein is then pushed down over the upper end of the container until its inner bead or inturned edge 11 passes flange 9, whereupon the flange will snap or spring out into locking engagement. The container is then removed from the support and is ready to be filled when positioned upright as in Fig. 4. When the container is filled, the top hoop with the top end member 3 therein may be telescoped into locking engagement with the upper retaining flaps of the container, the contents of the container ordinarily serving to bring the upper portion of the filled container to a cylindrical form so that the top hoop may be easily slipped into position.

It will be apparent that I have provided a device of exceeding simplicity and efficiency for assembling the improved container of my co-pending application or containers similar thereto. The adjustability of the cone carrying base plate 21 renders the device adaptable for setting up a great variety of lengths of container and it is obvious that by altering the shape of cone 23, a number of differing cross sectional forms may be accommodated. The simplicity of the device renders it possible to furnish packers with the same at small cost to stimulate the use of the containers disclosed in this application.

50 I have illustrated and described my improve-

ments in an embodiment which I have found very practical. I have not attempted to illustrate or describe other embodiments or adaptations as it is believed this disclosure will enable those skilled in the art to embody or adapt my improvements 5 as may be desired.

Having thus described my invention, what I claim as new and desire to secure by Letters Patent is:

1. A device for use in assembling containers, 10 comprising an upright having a base thereon adapted to hold the upright in fixed operative position on a supporting surface, a top disk fixedly mounted on said upright and having a diameter corresponding to the internal diameter 15 of the container to be assembled, and a base plate adjustably mounted on said upright for vertical adjustment thereon and provided with a centering cone slidably embracing the upright at the apex of the cone, the diameter of said 20 cone at its base corresponding to the internal diameter of the container.

2. A device for assembling cylindrical containers, comprising means for distending a container at one end thereof, means for supporting 25 said means, said distending means being fixedly secured to said supporting means, a base for mounting said supporting means in fixed operative position on a supporting surface, and means for distending the other end of said container, comprising a member corresponding in 30 shape and size at its base to the internal shape of the container and tapering to an apex slidably on said supporting means, and means for adjustably securing said member to said supporting 35 means.

3. A device for assembling cylindrical containers, comprising means for distending a container at one end thereof, means for supporting 40 said means, said distending means being fixedly secured to said supporting means, a base for mounting said supporting means in fixed operative position on a supporting surface, and means for distending the other end of said container, 45 comprising a member corresponding in shape and size at its base to the internal shape of the container and tapering to an apex at said supporting means.

JAMES E. ANNEN. 50
